ATTORNEY.

UNITED STATES PATENT OFFICE

CHRISTIAN L. SAAL, OF PATERSON, NEW JERSEY

WINDING MACHINE

Application filed February 26, 1929. Serial No. 342,908.

In winding machines in which the packages being wound have their axes horizontal and are rotated by having whirls on their cores resting on subjacent rotary driving wheels it is known to support a roller under each package so that when the latter attains a predetermined diameter it will peripherally engage the roller and thereby have its whirl raised out of contact with the driving wheel so that the driving will be stopped. This invention has for its object to provide for support of the roller by means which will not only be adjustable substantially horizontally and vertically—horizontally, so that the roller may be brought into some desired relation to the vertical plane of the axis of the package, and vertically, so as to determine the diameter of the package—but which may be manufactured at the minimum of expense and readily applied to any winding machine of standard type.

In the drawings,

Fig. 1 is a side elevation, partly in section on line 1—1, Fig. 2, of so much of a winding machine as embodies the invention in one form thereof;

Fig. 2 is a front elevation;

Fig. 3 is a plan of said form;

Fig. 4 is a side elevation and plan, partly broken away, of a detail;

Fig. 5 shows, partly in plan and partly in section, the bearing support for the roller;

Fig. 6 is a side elevation of another form, with a part of the machine frame shown in section;

Fig. 7 is a front elevation of this form; and

Fig. 8 is a plan thereof.

Let 1 designate the usual pair of horizontal bars forming a part of a winding machine frame of standard type; 2 the driving wheel carried by and rotating with a horizontal shaft 3; and 4 a pair of brackets formed with guide-ways 5 for the package trunnions, the core of which package may as usual consist of a spindle 6 (whose ends form said trunnions) having a driving whirl 7, which receives the driving contact of the wheel 2, and a spool 8 removably fitted on the spindle and on which the winding of the thread or yarn is directly effected.

According to this invention the roller 9 with which the periphery of the package contacts when the predetermined diameter of the latter has been attained is journaled in a bracket which is adjustable substantially horizontally and vertically and is angular in plan and has one arm supporting the roller and the other affixed to the frame, its angular form as specified making it very inexpensive to manufacture and readily adapted to fit any standard frame and be capable of the adjustments mentioned.

In the form shown in Figs. 1 to 4 this bracket is constructed as follows: An elongated strip 10 has a slot 11 extending longitudinally from one end thereof and a hole 12 (preferably square) at the other end. A bearing support for the roller 9 is formed by a headed pin 13 whose reduced stem 13a penetrates the slot 11 and also a washer 14 and a nut 15, the former being adapted to abut a shoulder 13b on the pin and the parts 14 and 15 being thereupon adapted to clamp the strip when the nut is screwed up tight. Another part of the bracket comprises a plate 16 bent to a right angle and having one portion or wing 16a thereof provided with a hole 16b and the other wing 16c thereof formed with a slot 16d which extends parallel with the line of bend of the plate. This slot receives a bolt 17 (Figs. 1, 3 and 4) which has a square portion 17a fitting the hole 12 in the strip 10 and also a nut 18 and a washer or washers 19 to coat therewith to clamp strip 10 to the wing 16c of plate 16, with the bolt penetrating slot 16d. In the normal position the strip 10 extends substantially perpendicular with reference to slot 16d, as shown in Fig. 1. Wing 16a of the plate bears against both bars 1 and is rigidly held thereagainst by a screw 20 which penetrates hole 16b and is screwed into a plate 21 between which and wing 16a the bars are clamped by the screw. The construction is such that the bracket is adjustable both horizontally and vertically so as to change the position of the roller in either of these directions transverse of the axis of the package—horizontally, by shifting that part thereof which is constituted by the bearing support for the roller lengthwise of that part

thereof formed by strip 10, and vertically, by shifting the strip lengthwise of the bend of plate 16. Both parts 10 and 16 may be of sheet metal.

- 5 Referring, now, to Figs. 6, 7 and 8: Here the bracket is in one piece. It consists of a T-shaped piece of sheet metal having the head 22 of the T, forming one arm of the bracket, bent into a plane perpendicular to the stem 23 thereof. The stem 23 has extending from its free end a longitudinal slot 24 in which a suitable bearing support 25 may be arranged. The arm 22 of the bracket has a slot 26 extending parallel with the bend in the piece and a washer 27 abutting it which are penetrated by a screw 28 which extends between the frame bars 1 and is screwed into a plate 29 which coacts with the washer to clamp said arm to the bars 1 on said screw being screwed up tight. Here again the construction is such that the bracket is adjustable both horizontally and vertically to change the position of the roller in either of these directions.
- 25 In the first form on the wing 16c of the plate, and in the second form on the arm 22 of the bracket, I preferably provide a scale 30, which may be marked with suitable indices, whereby the elevation of the roller and hence 30 the diameter which the package will attain before the winding is stopped may be determined.

Frags of the windings wind around the bearing device, accumulating to such a 35 degree as in time to stop rotation of the roller if they are not removed. This is possible by removal (on loosening nut 15) of the bearing device and roller as a unit, such removal being in turn possible by slot 11 being opened 40 ended.

Having thus fully described my invention, what I claim is:

In a winding machine, an attachment for stopping rotation of a spool resting, with its 45 axis horizontal, on a rotary driving member, including, in combination, a plate bent to substantially a right angle and having the wings formed both sides of its bend arranged in upright planes, one wing forming the supporting portion of the plate and the other having an upright slot, a flat strip bearing against the latter wing, means, penetrating the slot and strip, to secure the latter rigidly to the second wing, a bearing device secured 50 to the second wing, and a spool-engaging roller journaled on the bearing device.

In testimony whereof I affix my signature.

CHRISTIAN L. SAAL.
